MOTOR OPERATED MACHINE UNIT

Harry R. Van Deventer, New York, N. Y., assignor,
by mesne assignments, to General Motors Cor-
poration, a corporation of Delaware

Original application October 12, 1926, Serial No.
141,213. Divided and this application October
2, 1929, Serial No. 396,817. Renewed April 19,
1934

4 Claims. (Cl. 230—139)

This invention relates to a combination and arrangement of units of apparatus and the principles thereof may be applied to a variety of purposes.

5 The invention described and covered herein is the outgrowth of the development of apparatus for use in a mechanical refrigeration machine and more specifically this invention pertains thereto.

10 One object of this invention is to provide a combination of motor and pump which may be used for a variety of purposes, and in which all belts and gearing between the motor and pump are eliminated.

15 Another object is to provide a combined motor and pump with an enclosing housing therefor whereby the stuffing box usually surrounding the pump shaft is eliminated.

Another object of my invention is to provide 20 a compact efficient arrangement for securing a hermetically sealed motor pump unit.

25 A further object is to accomplish a major assembly of apparatus whereby a plurality of cooperating unit structures may each be independently and separately assembled and tested before being associated with its cooperating units and whereby any unit may be removed from the major assembly in toto for replacement purposes.

30 A still further object is to provide a method of mounting the motor pump assembly whereby noise and vibrations thereof are not transmitted to the refrigerator box, for example.

Other and further objects and improvements 35 will more fully hereinafter appear.

This invention is shown and will be described as applicable to a compressor for mechanical refrigeration apparatus, and is particularly advantageous for use in the small units commonly employed with household refrigerators now in extended use. However, the same may be applied to other apparatus by those skilled in the arts.

40 My invention may be understood by reference to the accompanying drawings, wherein—

Figures 1 and 1A represent a vertical section through the assembled units of the compression or "high-side" of a refrigeration machine unit embodying my invention;

50 Fig. 2 is a cross section on the line 2—2 of Fig. 1; and

Fig. 3 is a perspective view of the lower portion of a refrigerator and the compression or "high-side" of a refrigeration machine mount-

ed therein the top and one side thereof being removed to facilitate illustration.

1 denotes a main frame or casing, preferably tubular in form and comprising the support for the unit, having therein a partition 2, shown as 5 an integral inwardly extending flange forming a separating wall between two distinct chambers 5 and 5a.

Within the chamber 5 and mounted on one side of the main frame is a pump or compressor 10 unit 6 while within the chamber 5a and mounted on the other side of the main frame is the motor. The compressor unit consists of end plates 1, 1' supporting and forming bearings for a shaft 8 carrying pump rotors 9, the pump 15 illustrated being a rotary two stage type, although any other form of pump may be used. The partition 10 and cylinder or body portions 11 of the pump are secured together and to the respective end plates by any suitable means such as bolts, one of which is indicated at 12.

20 The construction and operation of the pump unit is not described in detail, because not constituting the subject of the present claims, and not necessary to an understanding thereof.

25 The foregoing pump may be assembled and tested as a separate unit from the other portions of the cooperating apparatus hereinafter described. When ready for service this unit pump structure is placed within the chamber 5 and 30 secured in position therein with the bearing 7 extending through the aperture provided in the partition 2. Any suitable securing means may be used, such as the clamps 13 secured to the partition 2 by means of screws as shown and 35 spaced around the periphery of the end plate 7.

The driving connection includes inner end of the shaft 8 which is splined, as indicated at 14, to engage the splined end of the shaft 15 upon which is mounted the rotor 16 of a prime mover 40 or electric motor (an alternating current motor is shown). The pole pieces of the motor are indicated at 17 as provided with field windings 18. The casing 1 has a plurality of internal ribs 20 upon which the field or stator of the motor is 45 pressed or otherwise secured. The motor shaft carries the movable portions 21 of the usual centrifugal starting switch, the stationary portions of which are indicated at 22 as mounted upon the bearing 23 which projects inwardly from the 50 head or closure member 3 which is sealed to the main frame. This head or closure member also carries the terminals of the windings 18 of the motor, one of which terminals is shown at 24 as insulated from the head or closure member 3. 55

The described motor unit drives the pump unit heretofore described.

I do not describe in detail the construction and operation of the electric motor as this may be 5 of any suitable construction. I have shown a known form of splitphase alternating current motor, but it is obvious that any other motor may be used within the scope of my invention.

The motor and pump assembly may be used 10 as part of a refrigeration system in which event the assembly is connected to a condenser and an evaporator or "low side", as will be hereinafter described.

The intake for the pump or compressor 8 is 15 through the conduit or duct 27 which extends through the side of the main frame or casing 1 and through partition 2 communicating directly with the first stage of the pump by means of the horizontal duct 27'. The outlet or exhaust of 20 the pump is indicated at 28 within the chamber 5, so that the pump is located in what may be termed the pressure chamber 5.

It will be assumed that the motor and pump assembly are part of a refrigeration machine system that is properly charged with a liquid refrigerant such as ethyl chloride and a lubricant such as a heavy oil. The oil is introduced into the pressure chamber 5 to the level indicated by the dot and dash line 29 where it is maintained by 25 means of the baffle plate 30 that is secured to the flange 26 on the interior of the casing 1. The baffle plate 30 does not contact with the entire flange 26, but is spaced to restrict the opening or conduit 31 formed in the main frame or casing 1 and connecting the chamber 15 through 30 the opening 33 with the exterior at the top of the chamber 5.

The refrigerant in a gaseous state enters the pump through the conduit or duct 27, is 40 compressed in the pump and discharged from outlet pipe 28 into the chamber 5, at which time it is commingled with the lubricant. It is desirable to separate the lubricant from the refrigerant and this is accomplished in the above described 45 structure in part because the lubricant being heavier than the compressed gas will fall to the bottom of the chamber, the free gas particles passing through opening or conduit 31, and partly because the pump casing will be warm, due to 50 the friction of the moving parts therein and the heat of compression, which will cause the refrigerant to immediately boil off from the lubricant and, in turn, pass through the opening 31. In other words, a constant distillation takes place 55 of the refrigerant from the body of lubricant, thereby maintaining the body of lubricant at the desired density. It will also be observed that this method of separation of the refrigerant from the lubricant is advantageous over any method of 60 mechanical separation because it is a fractional distillation method insuring actual chemical separation of the refrigerant from the lubricant.

The closure member or head 4 is seated to the main frame or casing 1 to form chamber 5 and 65 is spaced from the plate 30 so as to form a chamber 32 in which liquid refrigerant collects. The chamber is provided with openings 33 and 34 by means of which the chamber is connected to any suitable form of condenser, to be hereinafter 70 referred to. The opening 34 is also connected to any suitable form of expansion valve and evaporator (not shown) by means of the T connector 35.

I will not describe in detail the refrigeration 75 cycle as this is well known and any known sys-

tem may be used with the pump and motor structure herein disclosed. However, the method of lubricating the pump and motor is important and is as follows:—

The body of lubricant surrounds the pump. 5 Two pipes or conduits 37 and 38, which respectively communicate with the bearings in the end plates 1' and 1, extend into the body of lubricant. By reason of the pump discharging into the chamber 5 there is pressure on the surface of 10 the lubricant. Consequently lubricant is forced up the pipe 37, into the bearing in the associated end plate 1', through the hole 39 in the shaft 8 and through transverse holes 40 to the inner surfaces 41 of the pump and through the bearing in 15 the opposite end plate 1. The hole 39 does not extend into the spline 14. Where a rotary pump is used, the described system of lubrication also forms the seal for the pump.

Lubricant is also forced up the pipe or conduit 20 38 into the bearing in the associated end plate 1. The bearing is provided with an annular groove or conduit 42 which communicates with a hole or conduit 43 in the motor shaft 15 by means of a transverse hole, not shown. Lubricant is forced 25 into the bearing 23 in the head 3 and the oil leaves the bearing via duct or conduit 44, finding its way to the bottom of the chamber 26 from whence it is drawn into the suction duct or conduit 27 through the aperture or conduit 45 communicating therewith. The lubricant is ultimately returned to the main body of lubricant in the chamber 5. The hole 15 does not extend into 30 the spline 14. Thus passages 38, 42, 43, 44 and 45 constitute a conduit for the passage of oil, 35 which conduit is connected with the compression intake duct.

By the foregoing arrangement a constant circulation of lubricant is maintained through the pump and motor bearings insuring positive and 40 efficient lubrication at all times.

The cooling of the motor and pump is accomplished by means of a fan 46 which is driven by a suitable electric motor 47, the armature shaft 49 thereof being supported in bearings 50 and 45 51.

Bearing 50 is supported in the end plate 3 but has no communication with the motor chamber 52 which is connected to the suction side of the pump. Bearing 51 is supported by the end plate 50 52 that is mounted upon the casing 53 of the motor 47. The casing 53 may be formed integral with the closure member or head 3 if desired. Suitable terminals, one of which is shown at 54, are provided for the fan motor and these terminals may be connected to the pump motor terminals in multiple so that one main connection 55 will serve for the terminals of both motors. Both 55 motors are controlled by the same thermostatic means which may be of any of the types commonly employed for such purposes.

The lubrication of the fan motor is accomplished by providing a reservoir 56 filled with lubricant and communicating with the ducts 57 and 58 leading respectively to the bearings 50 and 51. The ducts are supplied with the usual wick oilers or other means for supplying lubricant to the bearings. The reservoir 56 is filled through the screw capped opening 59.

The main frame or casing may include suitable 70 radial cooling fins 60 extending beyond the closure members 3 and 4 to form a base, and around these fins is placed an outer casing or shroud 61. The shroud may have an extension 62 enclosing the fan, with suitable vibration absorbing pack- 75

ing 63 therebetween. By this arrangement an air current generated by the fan will be drawn into the space between the casing 1 and the shroud 62, as indicated by the arrow 64 and discharged in the direction of the arrow 65, thereby cooling the pump and motor chamber.

The above described assembled unit may be mounted in a refrigerator box of the usual type. In Fig. 3 the bottom portion of such a box is shown and comprises a base 66, the ends 67 and 68 and a two-part partition 69. The top and one side of this compartment have been omitted for convenience in showing the interior arrangement of parts.

The motor-compressor unit is supported by means of the main frame 1 in the partition 69 by means of a packing strip 70, preferably of suitable non-metallic resilient material. Additional supporting means are provided for the shroud 62 and its associated parts. These supports are in the nature of cradles connected at 71 and 72 respectively on opposite sides of the partition 69. The elements 71 and 72 may be of any suitable resilient material and I have found leather straps to be effective. Strap 71 extends through openings in the shroud 62 and is secured to the casing 1, the opposite ends being supported upon pillars or blocks 73. A resilient packing 71a surrounds each strap 71 where it extends through the openings in the shroud 63 and supports the shroud.

Strap 72 is secured to and supports the end of the casing 1 outside of the shroud 62 and is supported on opposite sides of the shroud upon pillars or blocks 74, one only of which is shown in the drawings.

The resilient mountings for the pump and motor unit and the associated shroud prevent motor-pump and mechanical vibrations from being transmitted to the container and the refrigerator box.

The front 75 of the box-like container is provided with a plurality of openings or louvres indicated at 76, 77 respectively on each side of the partition 69. The condenser 78 is so positioned in front of one set of these openings that the air drawn through the openings in front of the condenser will pass therethrough and into the space between the casing 1 and the shroud 62 as heretofore described. The air is discharged into the opposite compartment of the container, passing out through the openings 76 therein, thereby maintaining a constant circulation of air for cooling purposes.

The condenser 78 is connected to the motor 23 and pump assembly by means of pipes 79 and 80, the pipe 79 being fitted into the opening 33 in the head 4 and the pipe 80 being fitted into the T connection 35 (Fig. 1).

The gases which are discharged from the pipe 28 into the chamber 5 and the gases which are distilled off from the body of lubricant pass through the opening 31, through the opening 33 and pipe 79 into the condenser 78, where the refrigerant is converted into a liquid. In the refrigeration cycle the condensed refrigerant passes into an evaporator through an expansion valve, neither of which are shown, because well known in the art, the connection for the expansion valve being from the T 35 and the return line 70 from the evaporator being connected to the duct 27. Since these constitute no part of the present invention no description thereof is given.

The condenser 78 may either be supported on the motor pump unit by means of pipes 79 and 80 or independently supported on resilient means

of the same general character as that used for supporting the pump and motor unit.

In describing the assembly of the complete unit shown in Figs. 1 and 1A, attention has been directed to the fact that each of the motors and the pump may be assembled and tested as independent units before being inserted in the casing 1. Furthermore, in the event of repairs it is only necessary to remove the particular unit rather than disassembling the complete machine in order to reach the part which needs repairing. Accordingly, where the term "unit pump" or "unit motor" is used, it is intended to include a unit which may be assembled and tested independently of the parts with which it is to be associated.

This application is a division of application Ser. No. 141,213, filed October 12, 1926.

Modifications may be made in the arrangement and location of parts within the spirit and scope of my invention, and such modifications are intended to be covered by the appended claims.

I claim:

1. A combined motor and pump structure comprising a hermetically sealed casing forming two chambers, a complete self-contained pump structure removably mounted in one chamber, a motor mounted in the other chamber, an operating shaft for the pump structure, a shaft for the motor coaxial with the pump shaft, and means separately connecting the adjacent ends of said shafts, said pump structure being removable from its chamber of the casing and from the motor mounted in the other chamber and operable outside the casing as a unit.

2. A combined motor and pump structure comprising a hermetically sealed casing, a partition dividing said casing into two chambers, a complete self-contained pump structure in one chamber removably secured to said partition, a motor mounted in the other chamber, an operating shaft for the pump structure, a shaft for the motor coaxial with the pump shaft, and means separately connecting the adjacent ends of said shafts, said pump structure being removable from its chamber of the casing and from the motor mounted in the other chamber and operable outside the casing as a unit.

3. In combination a high pressure discharge chamber, a body of lubricant in said chamber, a rotary pump in said chamber including a substantially cylindrical casing, a shaft passing through said casing, a bearing for said shaft in a wall of said chamber, said shaft passing through said bearing and wall, a rotor on said shaft in said casing having vanes extending to said casing, a high pressure lubricant passage in said shaft having an open connection to said body of lubricant, a lubricant flow connection from said lubricant passage to a portion of the space between said shaft and bearing, a gas intake for said pump and another lubricant flow connection from another portion of the space between said bearing and shaft to said intake, said lubricant flow connections being partially sealed from each other by said shaft whereby only a limited quantity of lubricant is permitted to flow from said high pressure chamber to said gas intake.

4. In combination a high pressure discharge chamber, a body of lubricant in said chamber, a rotary pump in said chamber including a substantially cylindrical casing, a shaft passing through said casing, a bearing for said shaft in a wall of said chamber, said shaft passing through said bearing and wall, a rotor on said shaft in

said casing, a high pressure lubricant passage in said shaft having an open connection to said body of lubricant, a lubricant flow connection from said lubricant passage to a portion of the space between said shaft and bearing, a gas intake for said pump and another lubricant flow connection from another portion of the space be-

tween said bearing and shaft to said intake, said lubricant flow connections being partially sealed from each other by said shaft whereby only a limited quantity of lubricant is permitted to flow from said high pressure chamber to said gas intake. 5

HARRY R. VAN DEVENTER.
